DESIGN FOR A COMBINED STOP AND TAIL LAMP LENS

Samuel M. Dover, Chicago, Ill.

Application May 23, 1936, Serial No. 62,808

Term of patent 7 years

To all whom it may concern:

Be it known that I, Samuel M. Dover, a citizen of the United States, residing at Chicago, in the county of Cook and State of Illinois, have invented a new, original, and ornamental Design for Combined Stop and Tail Lamp Lens, of which the following is a specification, reference being had to the accompanying drawing, forming a part thereof.

Figure 1 is a front view of a combined stop and tail lamp lens showing my new design;

Figure 2 is an edge view thereof; and

Figure 3 is a sectional view taken along the line 3—3 of Figure 1.

I claim:

The ornamental design for a combined stop and tail lamp lens substantially as shown.

SAMUEL M. DOVER.
